NEWSPAPER RECEIVER COMBINED WITH MAIL
BOX AND SUPPORTING POST
Raymond M. Fillion, 442 Miller St., Ludlow, Mass.
Filed June 5, 1964, Ser. No. 372,884
1 Claim. (Cl. 232—33)

This invention relates to newspaper receivers, and more particularly to newspaper receivers that are mounted on the same supporting post on which the rural type of mail boxes are mounted in the suburbs and open country.

When newspapers were first delivered out beyond the city homes where they could easily be placed in doorways and the like, newsboys and mailmen left them in the mailbox. This worked as long as the newspapers were of only a few pages, but in this present day, where nearly every issue of the paper contains a large number of pages, the rural mailbox, as big as it is, is still far too small to hold both a newspaper and mail, yet it is most desirable to have a receiver for the newspaper that will keep the same in a good readable condition no matter what the weather may be.

It is, therefore, the principal object of this invention to provide a newspaper receiver, combined with a mailbox and supporting post, that will be a separate safe and dry place for the newspaper to be placed, and supported by the same post that supports the mailbox.

Another object of this invention is to provide a newspaper receiver combined with a mail box and supporting post that can be adapted to nearly any existing mail box and post.

Another object of this invention is to provide a newspaper receiver and mail box and supporting post having the newspaper receiver located directly under the mail box which it supports, thereby receiving some protection from the elements by using the mail box as a cover.

Another object of this invention is to provide a newspaper receiver combined with mail box and support post, the latter having specially designed anchor rods protruding from the lower end thereof in a manner that will securely hold the post when the newspaper is being shoved into its receiver.

Still another object of this invention is to provide a newspaper receiver combined with mail box and supporting post, that has the receiver formed out of one single piece of sheet metal.

Other objects, features, and advantages of the invention will be readily apparent from the following detailed description of a preferred embodiment of the invention, taken in conjunction with the accompanying one sheet of drawings, in which:

FIGURE 1 is a perspective view of this invention.

FIGURE 2 is a vertical sectional view of this invention taken substantially along line 2—2 of FIGURE 1 as viewed in the direction indicated by the arrows.

FIGURE 3 is a vertical sectional view of this invention taken substantially along line 3—3 of FIGURE 2 as viewed in the direction indicated by the arrows.

Referring to the drawing in detail, a mail box supporting post 5 having a plurality of anchor rods 6 projecting outwardly from the lower side thereof and at right angle thereto in the position shown in FIGURE 1 of the draw-

2

ing, provides support for the newspaper receiver 7 that is securely mounted on top of the aforesaid post 5 by any desired means.

The newspaper receiver 7 consists of a single piece of sheet metal or its equivalent that is formed to have the configuration of a trapezoid when viewed from the end by having the two sides 8 bent upward as illustrated in FIGURES 1 and 3 of the drawing. The uppermost edge of each side 8 is vertically formed in order to contact the vertical lower sides 9 of a typical rural mail box 10 to which the aforesaid newspaper receiver is secured by means of a pair of spaced bolts 11. The aforesaid newspaper receiver 7 is shorter in length than the rural mail box 10, as one can see by looking at FIGURE 2 of the drawing.

The newspaper receiver is firmly fixed on top of the aforesaid post 5 by having the horizontally disposed flat bottom 12 suitably secured thereto.

While I have illustrated and described a certain preferred embodiment of my invention, it is to be understood that I do not thereby intend to limit my invention to the specific form disclosed, but contemplate that various modifications, substitutions, and alternative constructions may be effected without departing from the spirit and scope of the invention as defined in the appended claim.

I claim:

An invention of the character described, comprising a newspaper receiver that is made from sheet metal having the configuration of a trapezoid when viewed from the end, the angularly disposed sides having their upper edge vertically formed and adapted to receive the lower portion of a rural mail box therebetween, the said rural mail box being secured to the said newspaper receiver by a plurality of screws, and the horizontally disposed flat bottom of the said newspaper receiver being rectangular when viewed from the top and bottom, and said newspaper receiver being shorter in length than the said rural mail box, and the said newspaper receiver having the underside of the said flat bottom welded to the top of a metal post which is centrally located in relation to the length of the said newspaper receiver, and the lower portion of the said metal post having a plurality of anchor rods projecting outward as a cantilever at right angle to the said metal post and in vertical, radial, and equal spaced relation to each other, the said lower portion of the metal post with its anchor rods being in the ground when the said invention is set up and ready for use.
